UNITED STATES PATENT OFFICE.

WILLIAM HENRY PIERCE AND FRED ASPIN, OF ACCRINGTON, ENGLAND.

PICKER-CHECK FOR LOOMS.

No. 910,572.

Specification of Letters Patent.

Patented Jan. 26, 1909.

Application filed May 11, 1907. Serial No. 373,082.

To all whom it may concern:

Be it known that we, WILLIAM HENRY PIERCE and FRED ASPIN, residing at 60 Willows Lane, Accrington, in the county of 5 Lancaster, England, and 109 Willows Lane aforesaid, respectively, have invented certain new and useful Improvements in Picker-Checks for Looms; and we do hereby declare the following to be a full, clear, and exact 10 description of the invention, such as will enable others skilled in the art to which it appertains to make and use the same.

This invention relates to picker checks of looms for weaving.

15 It is usual to employ, at the present time, for the purpose of arresting the movement of a picker after it has impelled the shuttle from the box, that is to say on the completion of its operative stroke, a number of 20 strips of leather, or a block of leather, disposed upon the picker spindle, and having attached thereto one end of a check strap of which the opposite end is secured to a stud fixed in the front of the shuttle-box or to 25 any other convenient part of the loom. The length of this check strap is such, or can be so adjusted, that the buffer, although normally occupying a position upon the picker spindle close to the stud on the end thereof, 30 is not actually in contact with such stud, and on the picker striking the buffer the said strap is consequently placed in tension and absorbs the shock caused by the impact of the picker against the buffer.

35 A buffer and check strap, as above described, for arresting the movement of the picker, are not only expensive initially but rapidly deteriorate and require frequent renewal. Moreover, as would naturally be expected, it is found that the continual strain to which the check strap is subjected causes it to become permanently stretched or extended, and unless this is observed and remedied in due time the said check strap 45 ceases to perform its function, as the buffer takes up a position against the stud on the end of the picker spindle and receives the whole force of the blow of the picker. As a result of this the stud is driven off the end 50 of the picker spindle and damage done to the piece.

The object of this invention is to overcome the disadvantages attending the use of a buffer and check strap as above described 55 by providing a buffer which shall, essentially, be sufficiently elastic to absorb, alone or un-

aided, the shock caused by the blow of the picker, and at the same time sufficiently durable to withstand the repeated blows of the picker, and this we find we are able to accomplish by employing, to compose a buffer, a fibrous, semi-fibrous, or kindred material or substance, or in materials or substances, combined with india-rubber, or its equivalent. The material or substance combined 60 with the india-rubber or its equivalent is preferably of a distinctly fibrous nature and is preferably used in the form of a fabric, of which cotton sheeting, canvas, linen, and ramie cloth may be cited as examples, but 65 not necessarily so, and as alternatives may be mentioned cotton yarn, flax, hemp, wood-pulp, paper, and cork.

Such being the nature and object of our 70 said invention we will describe with reference 75 to the accompanying drawings an embodiment of the invention and mode of constructing the particular form of buffer illustrated.

In the drawings:—Figure 1 is an end view 80 of the form of picker buffer we have found in practice to give the best results; Fig. 2 is a side view thereof; Fig. 3 shows the buffer in position upon a picker spindle; and Figs. 4 and 5 are views, corresponding to Figs. 1 85 and 2, of a cap which we usually find it advantageous to employ in conjunction with the buffer.

In constructing buffers of this preferred 90 form we take preferably a cotton sheeting of suitable length and width and in the first place to one side of this we apply a thin layer or coating of india-rubber in a liquid or semi-liquid condition. The said cotton sheeting is then passed through heavy rollers 95 after which another layer or coating of india-rubber may be applied and the cloth again squeezed between heavy rollers and so on as often as may be required, the squeezing having the effect of forcing the 100 india-rubber into, but preferably not through, the cloth. The opposite side of the cloth is then treated in like manner. The said cloth is then wound or wrapped around a mandrel into the form of a tube, 105 as illustrated in Fig. 1, the said tube being thus composed of alternate layers of india-rubber and cloth. The tube is then vulcanized and cut into short lengths to form the buffers *a* as illustrated in Figs. 2 and 3. 110 To prevent the buffers being impaired or destroyed by the oil in which the pickers are

steeped, or by the acids in the oil, they are preferably coated at the ends and otherwise externally with celluloid or other material having like properties, or if desired they 5 may be impregnated therewith.

The buffer *a* is placed upon the picker spindle *c* so that it is in contact with the stud *d*, as shown in Fig. 3, and the bore or internal diameter *a*¹ of the buffer *a* is made 10 slightly less than the diameter of the spindle on which it fits so that the buffer firmly grips the spindle and is held securely in its place thereon. A cap or disk *b*, of raw hide, leather, compressed felt, or other suitable 15 material, provided with a central hole *b*¹, is preferably employed in conjunction with the buffer to receive the blow of the picker, the said cap *b* being placed upon the picker spindle in the position shown in Fig. 3. 20 The spindle *c* is supported in the loom in any appropriate manner, and the stud or abutment *d* is rigidly secured to its free end portion. The edges of the layers of material at one end of the buffer *a* bear against the 25 abutment *d*, and the cap *b*, when same is used, bears against the layers at the other end of the buffer.

The picker is of any approved construction and it slides upon the spindle *c*. The 30 picker is attached to the picking-stick by a strap in the ordinary approved way, and is operated by the said picking-stick. When the picker strikes the cap *b* the force of the blow is distributed over the edges of the 35 layers of textile material and india rubber, so that very little shock is transmitted to the abutment *d*.

In carrying out this invention any compound having the elastic properties of india 40 rubber may be used as the mechanical equivalent of india rubber.

We would have it understood that while we prefer to construct a buffer of the particular shape described and illustrated, and

of the materials and in the manner specified 45 with regard to the buffer shown in the drawings, as we believe that by so doing we obtain the best results, we do not bind ourselves to this particular shape, composition, or mode of construction. 50

For looms with a light pick the buffers need not be vulcanized.

We claim as our invention:—

1. The combination, with a picker-spindle provided with an abutment, of a resilient 55 picker buffer formed of agglomerate layers of textile material and india rubber, said layers being secured endwise against the said abutment so as to receive the blow of the picker upon their ends remote from the 60 said abutment.

2. The combination, with a picker-spindle provided with an abutment, of a resilient 65 picker buffer formed of agglomerate layers of textile material and india rubber, said layers being secured endwise against the said abutment so as to receive the blow of the picker upon their ends remote from the said abutment, and a protective cap covering the ends of the said layers where the 70 picker strikes to distribute the force of its blow.

3. The combination, with a supporting 75 spindle provided with an abutment, of a tubular picker buffer formed of a series of coils of textile material and india rubber encircling the said spindle and arranged endwise against the said abutment so as to receive the blow of the picker upon the ends 80 of the said coils remote from the said abutment.

In testimony whereof we affix our signatures, in presence of two witnesses.

WILLIAM HENRY PIERCE.

FRED ASPIN.
